(57) **CLAIM**

The ornamental design for a laser smoking device as shown and described.

DESCRIPTION

FIG. 1 is a side perspective view of the laser smoking device.

FIG. 2 is a front view of the laser smoking device.

FIG. 3 is a rear view of the laser smoking device.

FIG. 4 is a right side view of the laser smoking device.

FIG. 5 is a left side view of the laser smoking device.

FIG. 6 is a bottom view of the laser smoking device; and,

FIG. 7 is a top view of the laser smoking device.

The broken lines in the drawings depict portions of the laser smoking device that form no part of the claimed design.
